UNITED STATES PATENT OFFICE.

JOSEPH A. STEINMETZ, OF PHILADELPHIA, PENNSYLVANIA.

DESIGN FOR A VACCINATION-SHIELD.

SPECIFICATION forming part of Design No. 35,417, dated December 10, 1901.

Application filed November 15, 1901. Serial No. 82,459. Term of patent 7 years.

To all whom it may concern:

Be it known that I, JOSEPH A. STEINMETZ, a citizen of the United States, residing in the city of Philadelphia, county of Philadelphia, and State of Pennsylvania, have invented and produced a new and original Design for a Vaccination - Shield, of which the following is a specification, reference being had to the accompanying drawings, forming part thereof.

10 Figure 1 is a top plan view of a vaccination-shield, showing my new design. Fig. 2 is a sectional view on the line 2 2 of Fig. 1, and Fig. 3 is a sectional view on the line 3 3 of Fig. 2.

15 As shown in the drawings, the leading or material feature of my design consists of a curved

rim A, having the extension A', and a dome B, comprising the arched cross-pieces B' and the openings B". The cross-pieces B' have the ribs b thereon.

Having described my invention, what I claim as new, and desire to secure by Letters Patent, is—

The design for a vaccination-shield, as herein shown and described.

In testimony whereof I have signed my name to this specification in the presence of two subscribing witnesses.

JOSEPH A. STEINMETZ.
